UNITED STATES PATENT OFFICE.

DANIEL F. LEPLEY, OF CONNELLSVILLE, PENNSYLVANIA.

HOIST SKIP.

Application filed August 31, 1922. Serial No. 585,540.

To all whom it may concern:

Be it known that I, DANIEL F. LEPLEY, a citizen of the United States, residing at Connellsville, in the county of Fayette and State of Pennsylvania, have invented a new and useful Hoist Skip, of which the following is a specification.

This invention relates to hoist skips of that type utilizing a bottom closure which, when moved to open position, forms a chute to facilitate the delivery of the contents of the skip. These combined chutes and closures have been operated by means of tracks provided for that purpose, one form of this type of skip with its operating means being disclosed for example in Patent No. 1,304,784 issued to me on May 27, 1919 and Patent No. 1,379,869 issued to me on May 31, 1921.

Bottom closures of the kind mentioned have been found objectionable under some conditions. For example if a skip is brought to a stop at a point where the bottom closure is partly open and for some reason it becomes desirable to reverse the movement of the skip, it has been found impossible readily to lower the skip because the material carried thereby has become packed back of the partly opened closure or chute and thus interferes with the return movement of said closure under the action of the closing mechanism provided therefor.

One of the objects of the present invention is to overcome the disadvantages found in skips of similar types heretofore made by utilizing an undercut gate forming a part of the delivery chute and closure and which gate supports the load under normal conditions and will, when the closure is moved to shut position, cut through any material that may have banked up in the path of the gate.

Another object is to provide a skip which, because of the employment of an undercut gate, will trap any material that may leak past the gate, thus saving material that would otherwise be wasted in the shaft.

Another object is to so construct the skip and closure that the necessary travel of the closure is materially reduced, thus producing a quicker and easier action of the parts.

A further object is to provide a skip so shaped as to reduce breakage of coal or other material to the minimum when delivered thereto, the load being more accurately centered than heretofore.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is a side elevation of a hoist skip embodying the present improvements, one of the chute operating tracks being shown.

Figure 2 is a vertical section through the bottom portion of the skip and showing the combined closure and chute extended to delivering position.

Figure 3 is an enlarged section through a portion of the skip and taken on the line 3—3, Figure 1.

Figure 4 is a similar view showing a slightly modified form of the structure.

Referring to the figures by characters of reference 1 designates the body portion of the skip, the same being secured within a suitable frame 2 adapted to be guided in the usual manner within a mine shaft. The skip is provided with an inclined bottom 3 the lower edge of which terminates back from the plane of the wall 4 of the body and the lower portion of the wall 4 merges into a downwardly and inwardly inclined bottom section 5 spaced from the bottom 3 and cooperating with the upper portion of the bottom 3 to form a hopper. The side walls of the body extend outwardly beyond the bottom portions 5 and have their free edges extending from the lower edge of the bottom 3 to the lower edge of the wall 4 and along lines intersecting the plane of the wall 4.

Reinforcing strips 6 are secured to the sides of the body and extend downwardly below the lower end of the bottom 3 thus to form bearings 7 in which is mounted a pivot rod 8. On this rod are pivotally mounted the side wings 9 of a combined chute and closure 10, the bottom of this chute being adapted to extend below the bottom 3. The side wings 9 are provided between their ends with a segmental gate 11 adapted to close

the space between the bottom portion 5 and the bottom 3 when the chute bottom 10 is extended upwardly as in Figure 1. Thus the gate 11 will support the contents of the 5 body 1.

The wings 9 lap the outer faces of the sides of the body and the gate 11 is not connected to these wings but, instead, to segmental supporting plates 12 riveted or otherwise secured to the bottom of the chute 10. The side walls of the body are adapted to extend between the wings 9 and segmental plates 12 as clearly shown in Figure 3.

A supporting frame 13 is arranged under 15 the bottom 3 of the skip and has a bell crank 14 fulcrumed thereon at '4'. One arm of this bell crank has a roller 15 adapted to work within a track 16 located in the path of movement of the roller. The other arm of 20 the bell crank is connected by a link 17 to the inner end portion of the chute 10.

By referring to Figure 1 it will be noted that when the chute is closed the upper free end thereof is substantially in line with the 25 reinforcing strips 18 on the corresponding face of the body 1 and will not, therefore, become hung upon any of the structure within the mine shaft. Furthermore when the parts are thus located the load is supported by the gate 11 situated adjacent the 30 center line of the skip. It will be apparent, by referring to Figure 1, that the load will be substantially balanced within the skip because the pocket formed below the bottom portion 5 and back of the chute 10 is not filled with any part of the load but, instead, the lower portion of the load is distributed evenly in the lower portion of the skip. The provision of this pocket behind the closed 35 chute is advantageous because any material that may leak past the gate 11 will be trapped in the pocket and thus saved.

When the skip approaches the point where the delivery of its contents is to take place, 40 the roller 15 will enter the track 16 and be shifted thereby so as to cause the bell crank 14 to transmit motion through link 17 to the chute 10. Thus the chute will be swung from the position shown in Figure 1 to the 45 position shown in Figure 2, the gate 11 passing from under the load and being brought to a position where it will serve as a means for deflecting the outflowing stream of material into the space between the gate 11 and the bottom of the chute 10. The downward 50 movement of the skip will result in the reversal of the movement of the chute and if this reversal should take place before all of the material has been delivered from the 55 chute, the gate 11 will cut through the stream of material and cut off the escape of the material above the gate while that portion trapped between the gate and the closing chute will be retained in the pocket 60 formed back of the chute. Thus there will

be no waste of material and there will be no danger of the skip becoming stalled in the shaft.

If desired the segmental plates 12 can be offset where connected to the gate 11, as 70 shown at 19 in Figure 4. Thus supporting rollers 20 can be located on the sides of the body 1 at proper points to engage and support the edges of the gate when closed. By providing these rollers the segmental plates 75 will be relieved to a large extent of the weight of the load to which the gate is subjected.

As shown in Figure 1 one wall of the body is preferably curved, as at 21 thus to overhang the bottom of the skip, this curved wall extending to the top of the skip and leaving an inlet space 22 through which material can be delivered to the skip. By curving the wall 21 located opposite the point of loading the coal or other material entering the skip in a stream will come against this curved wall and be deflected downwardly along curved lines, thus reducing breakage 85 to the minimum.

It will be noted that when the chute is closed it is not in a vertical position. Thus it can travel more quickly from its closed position to its lowered or delivering position than would be possible should the closed 90 chute be vertically disposed and the degree of movement correspondingly increased. By thus reducing the travel quicker and easier action of the chute can be effected.

Importance is attached to the use of the 100 external hangers 6. These hangers act as a bail or sling to support the outer end of the hinge shaft 8 independently of the support the shaft gets from its attachment to the outer end of the unsupported plate or bottom 105 3 which, in itself, is not strong enough to carry the load. Thus the structure is materially strengthened.

What is claimed is:—

1. A hoist skip including a body having 110 an inclined lower bottom portion and an inclined upper bottom portion converging downwardly and providing an outlet space therebetween, a combined chute and closure hingedly connected to the lower end of the 115 lower bottom portion and cooperating with the sides of the skip body, when closed, to form a pocket under the upper bottom portion, an undercut gate movable with the chute for closing the outlet space, and means for shifting the chute to closed and 120 delivering position during the movement of the skip.

2. A hoist skip having downwardly converging bottom portions forming an outlet 125 opening therebetween, one of said bottom portions being extended below the other, a combined chute and closure hingedly connected to the lower bottom portion and co-operating therewith, when closed, to form 130

a pocket below the other bottom portion, and a cut-off gate movable with the closure to support material in the skip when the chute is closed.

- 5 3. A hoist skip having downwardly converging bottom portions forming an outlet opening therebetween, one of said portions extending below the other and terminating between the planes of opposed walls of the 10 skip, and a combined chute and closure hingedly connected to the lower bottom portion and supported, when closed, along a plane intersecting the plane of one wall of the 15 skip.
- 15 4. A hoist skip having downwardly converging bottom portions forming an outlet opening therebetween, one of said portions extending below the other and terminating between the planes of opposed walls of the 20 skip, a combined chute and closure hingedly connected to the lower bottom portion and supported, when closed, along a plane intersecting the plane of one wall of the skip, and an arcuate undercut gate movable with the 25 chute to close or open the outlet between the bottom portion.

5. A hoist skip having downwardly converging bottom portions forming an outlet opening therebetween, one of said portions extending below the other and terminating between the planes of opposed walls of the skip, a combined chute and closure hingedly connected to the lower bottom portion and supported, when closed, along a plane intersecting the plane of one wall of the skip, and an arcuate undercut gate movable with the 30 chute to close or open the outlet between the bottom portion, said gate being spaced from the bottom of the chute and constituting deflecting means when the chute is open.

40 6. A hoist skip having downwardly converging bottom portions forming an outlet opening therebetween, one of said portions extending below the other, a combined chute and closure hingedly connected to the lower bottom portion and having side wings lapping the sides of the skip body, supporting plates secured to the chute and movable between the sides of the skip body, and an 45 arcuate undercut gate carried by said plates and movable with the chute to open or close the outlet opening.

50 7. A hoist skip having downwardly converging bottom portions forming an outlet opening therebetween, one of said portions extending below the other, a combined chute and closure hingedly connected to the lower 55

bottom portion and movable upwardly to closed position to form a pocket below the upper bottom portion, plates movable with the combined chute and closure, and an arcuate undercut gate carried by the plates and movable into or out of closing position across the outlet opening, the side walls of the skip extending between said plates and the sides of the chute.

5 8. A hoist skip having downwardly converging bottom portions forming an outlet opening therebetween, one of said portions extending below the other, and a combined 10 chute and closure hingedly connected to the lower bottom portion and adapted, when closed, to provide a storage pocket between the upper and lower bottom portions.

9. A hoist skip having downwardly converging bottom portions forming an outlet therebetween, a chute movably connected to one of said bottom portions, means controlled by the movement of the skip for shifting the chute into and out of delivering 15 position, and an undercut gate movable with the chute for closing the outlet when the chute is out of delivering position, said gate constituting a deflector for material being delivered through the chute.

10. A hoist skip having a downwardly inclined bottom leading to an opening, hangers secured to opposed walls of the skip, a hinge shaft supported by the hangers adjacent the bottom of the opening, and a 20 chute hingedly supported by the shaft.

11. A hoist skip having a downwardly inclined bottom leading to an opening, hangers secured to opposed portions of the skip, and a chute supported by the hangers 25 and mounted for swinging movement about an axis extending parallel with and close to the bottom of the opening.

12. A hoist skip having a downwardly inclined bottom leading to an opening, 100 hangers secured to opposed portions of the skip, a chute supported by the hangers and mounted for swinging movement about an axis extending parallel with and close to the bottom of the opening, and an undercut load 105 supporting gate movable with the chute.

In testimony that I claim the foregoing as my own, I have hereto affixed my signature in the presence of two witnesses.

DANIEL F. LEPLEY.
